(57) **CLAIM**

The ornamental design for a light bulb, substantially as shown and described.

DESCRIPTION

FIG. 1 is an elevational view of an embodiment of the invention;

FIG. 2 is an elevational view of the same embodiment rotated 90 degrees;

FIG. 3 is a top view of the embodiment of the invention; and,

FIG. 4 is a plan view of the embodiment of the invention. The elements for which the design is claimed are shown in solid lines, the dashed lines showing environmental structure.
